CLAIM

The ornamental design for a linear surgical fastener applier, substantially as shown and described.

DESCRIPTION

FIG. 1 is a side perspective view of a linear surgical fastener applier showing our new design;

FIG. 2 is a side elevational view thereof;

FIG. 3 is an end elevational view as seen from the right of FIG. 2;

FIG. 4 is an end elevational view as seen from the left of FIG. 2;

FIG. 5 is a top plan view thereof; and

FIG. 6 is a bottom plan view thereof.

Fig. 3.

Fig. 4.
